UNITED STATES PATENT OFFICE.

CURRY SAMUEL SMALL, OF COOPERSTOWN, PENNSYLVANIA.

COMBINED BOOK-REST AND CHART-SUPPORT.

SPECIFICATION forming part of Letters Patent No. 370,824, dated October 4, 1887.

Application filed May 13, 1887. Serial No. 238,113. (No model.)

To all whom it may concern:

Be it known that I, CURRY SAMUEL SMALL, a citizen of the United States, residing at Cooperstown, in the county of Venango and State of Pennsylvania, have invented a new and useful Improvement in Combined Book-Rests and Chart-Supports, of which the following is a specification.

My invention relates to an improvement in combined book-rests and chart-supports; and it consists in the construction and arrangement of the parts of the same, which will be more fully hereinafter described, and pointed out in the claims.

15 The object of my invention is to provide a combined book and chart rest for use in exhibitions and schools, which is so constructed as to adapt it to be folded into a small space and to be elevated or lowered, as may be desired, the parts of which are simple and effective in their construction and operation, strong and durable, easily handled and understood, positive in their result, and cheaply manufactured. I attain this object by the mechanism 20 illustrated in the accompanying drawings, wherein like letters of reference indicate similar parts in the several views, and in which—

Figure 1 is a perspective view of my improved device shown adjusted for use. Fig. 30 2 is a like view of the same with the parts shown as folded and adjusted for disuse. Fig. 3 is a front elevation of the same. Fig. 4 is a side elevation thereof. Fig. 5 is a detail view of the plate C'.

35 A indicates a central standard, which is mounted in a tripod, B, and passes through a casting, B', to which it is adjustably secured by a set-screw, W, and to which the legs b of the tripod are pivotally secured. The casting 40 B' is formed with a series of recesses, b', in which the upper ends of the legs b engage, and are pivotally mounted therein, being pivoted at the point b'. On the top portion of the casting B' a circular plate, B², is mounted, and 45 is provided with a series of circular slots, b³, which are engaged by binding or set screws b⁴, which pass therethrough and into the top portion of the casting B', and retain the said circular plate B² in contact with the said casting, and are so adjusted as to allow the said 50 plate to have a revolution when desired; or, if

it is desirable, the said plate may be rigidly secured in connection with the top portion of the casting B'. Formed integrally with the lower edge of the said circular plate B² and 55 depending therefrom are three lugs, b⁵, which are adapted to be turned over the top portions of the legs b and retain the same in operative resting position, as shown in Fig. 1. When it is desired to fold the legs of the tripod for 60 transportation or other purposes, the circular plate is turned until the said lugs disengage from the top portion of the legs b, as shown in Fig. 2, when the said legs may be turned in toward the vertical position of the central 65 standard or folded.

To the top portion of the central standard, A, a cross-bar, C, is secured, and the rear portion thereof has a recessed plate, C', which is secured thereto, and with which the head of a 70 screw-threaded bolt, c, engages, and has sliding movement therein. The bolt c passes through the central standard, A, at this point, and is engaged by an adjusting winged nut, c'. The said recessed plate C' is formed with circular recesses or depressions, both vertical and horizontal, which engage with the central standard, and thereby provides a more steady support between the two parts. The top portion of the cross-bar C has metallic loops c² 75 secured thereto, which are adapted to retain the map or chart rods and support the same when open, or when rolled up the said maps or charts may be inserted in the said loops and be held thereby. To the lower edge of 80 the said cross-bar C a bar, C², is hinged by means of the hinges c³, and to this lower bar, C², a folding book-rest, D, is secured. This book-rest D is constructed of a series of longitudinal bars pivotally connected to each other, 85 and are adapted to be folded up against the said bar C², as will be readily understood.

To one side of the central standard, A, adjacent to the cross-bar C, a slotted adjustable supporting arm, E, is secured, and controlled 90 in its position by a clamping winged nut, d, which engages with a screw-bolt, d', passing through the said standard at right angles to the upper bolt, c. This bolt d' passes through the slot e in the arm E, and when the said arm is 95 adjusted as desired the said nut is screwed against the same and clamps the arm against 100

the central standard, A. The one end of this arm E is provided with a stud or pin, e', which engages with an aperture in the lower bar of the book-rest D, and thereby retains the same in an inclined supported position, as shown in Fig. 1.

When it is desired to fold the several parts of the device, as shown in Fig. 1, the nuts c' and d are loosened until the bar C and the arm E may be turned down against the standard A in a folded position, as shown in Fig. 2, and the legs b of the tripod in like manner folded in against each other, as hereinbefore described.

15 The advantage of my improved form of chart-rest and book-support is, that the parts remain intact at all times, and when folded provide an adjustable and convenient device, and which may be readily adjusted for use 20 when desired.

The parts are all readily and easily operated, requiring no mechanical skill to understand their several relative connections and adjustments.

25 The novelty, utility, and adaptability of my improved device being apparent, it is unnecessary to further enlarge upon the same herein.

Having thus described my invention, what I 30 claim as new, and desire to secure by Letters Patent, is—

1. In combination with the central adjustable standard, A, the casting B', supporting the standard and having recesses formed in 35 its side, the legs pivoted in said recesses, and the flat slotted plate B², turning on the top of the casting, and having lugs b⁵, projecting downward from its edge, adapted to engage with the legs and hold them in a supporting 40 position, substantially as described.

2. In a combined chart and book rest, the combination of the central standard, the cast-

ing B', having the recesses formed therein, the legs b, engaging with the recesses in said casting, the adjusting-screw W, the slotted plate 45 B², having the depending lugs d³, and the binding-screws b⁴, substantially as described.

3. The combination, with the central adjustable standard, A, of the cross-piece C, having the slotted metallic strip C', constructed as set 50 forth, the bolt e, and the winged nut e', substantially as described.

4. In a combined chart and book rest, the combination, with the central standard, A, of the cross-piece C, the folding book-rest secured to the lower edge thereof, the metallic loops secured to the top portion thereof, and the adjustable supporting-arm E, substantially 55 as described.

5. In a combined chart and book rest, the combination, with the central vertically-adjustable standard, A, of the folding tripod and the cross-piece C, adapted to be folded down against the standard A in the same plane therewith, the book-rest D, hinged to the lower portion thereof, the supporting adjustable slotted arm E, the bolts c and d, and the nuts d and c', engaging said bolts, substantially as described.

6. In combination with the central vertically-adjustable standard, A, the cross-piece C, adapted to be folded down against the standard A, the slotted metallic strip C', secured to the rear of the strip C, the book-rest D, hinged to said strip C, and the slotted adjusting-arm 75 E, substantially as described.

In testimony that I claim the foregoing as my own I have hereto affixed my signature in presence of two witnesses.

CURRY SAMUEL SMALL.
